SEPARABLE FASTENER

Gideon Sundback, Meadville, Pa., and Gustaf Dahlén, St. Catharines, Ontario, Canada, assignors to Hookless Fastener Company, Meadville, Pa., a corporation of Pennsylvania

Application February 4, 1932, Serial No. 590,872
Renewed October 21, 1933

7 Claims. (Cl. 24—205)

Our invention relates to multiple interlocking fasteners which are adapted to be opened and closed by movement of a slider along a series of interlocking elements.

5 The principal object of our invention is to devise an improvement in or a modification of the invention described and claimed in the pending application of Gideon Sundback, Serial No. 415,721, filed December 21, 1929. In accordance 10 with the earlier application, the slider is provided with suitable locking means for preventing accidental opening of the fastener, and the present invention particularly aims at an improved construction of such locking slider which 15 will be relatively simple, cheap to manufacture, durable and reliable in use.

Another object is to provide an improved flexible pull member having a ring connection with the slider body in which the flexible member is confined to one position on said ring. The 20 purpose of this improvement will appear further on in the specification.

The objects and advantages will appear more 25 fully during the course of the specification. In the accompanying drawing we have shown for purposes of illustration, one embodiment which our invention may assume in practice. In the drawing:

Fig. 1 is a plan view of a portion of a multiple 30 interlocking fastener with a slider embodying my invention;

Fig. 2 is a longitudinal central section through the slider showing the fastening elements there- 35 in;

Fig. 3 is a side view of the slider and cooperat- 40 ing portions of the fastener stringer;

Fig. 4 is an end view of the slider and cooperat- 45 ing portions of the fastener;

Fig. 5 is a plan view of the slider with the 50 locking and pull attaching member removed;

Fig. 6 is a cross sectional view on line 6—6 of Fig. 5;

Fig. 7 is a perspective view of the locking and 55 pull attaching member;

Fig. 8 shows the flexible pull member;

Figs. 9 and 10 are cross sections of the ring 60 on lines 9—9 and 10—10 respectively of Fig. 4; and

Fig. 11 is a cross section through the interme- 65 diate part of the locking member.

The fastener illustrated is of the well known 70 interlocking type having a pair of stringers 12 to which are attached in properly spaced relation the interlocking fastener elements 13 which

are adapted to be quickly engaged or disengaged by movement of a slider 14 along the elements.

In carrying out the invention, in one convenient form our improved slider may be of any suitable size and shape having the usual channeled body which may be briefly described as comprising spaced apart wing portions 15 and 16, side flanges 17 and an integral neck connection 18. The slider may be formed by stamping or pressing from a single sheet of metal or may be constructed in several parts suitably united together and may be of any form which will enable it satisfactorily to perform its functions.

A suitable lug or projection 19 is formed on the upper wing of the slider to provide a fulcrum, 70 upon which is pivoted a movably mounted elongated locking member 20, the connection being effected by a projection 21 on the locking member engaging in an aperture 21a in the lug or by any other suitable means. As noted in Fig. 11 75 the locking member is of T section so as to provide guide grooves 22 to permit a sliding connection with the flexible pull member. This elongated locking member 20 may be referred to as a locking member or as a pull attaching member 80 since it has a double function. At its forward end the locking member has its web portion cut away and the remaining portion bifurcated and bent down to provide a locking projection 23 extending at right angles from the bar, and a longitudinal stop projection 24 which cooperates 85 with the stirrup portion 25 of the slider body to permit limited movement of the forward end of the locking member while pivoting about its fulcrum. The projection 24 is bent at an angle 90 so as to provide a ledge to engage under a wire 95 spring 25a which is anchored to the slider at one end and extends longitudinally of the slider body. The manner of anchoring the spring is best illustrated in Fig. 6. The wire is placed in a shallow recess 26 in the slider body and preferably by means of a double edged tool the metal on opposite sides of the groove is forced over the spring as indicated to anchor one end, leaving the other end of the spring free to render the spring more 100 flexible. It will be observed that the normal tendency is to urge the locking member downwardly into locking position at all times.

The pull member may assume any convenient form but preferably comprises a flexible bead 105 chain 27 having at one end a link 27 connected to a split ring 29 whose ends are pressed into the grooves 22 of the locking member. The ring can slide along the locking member, but cannot rotate about its own axis. This ring is preferably 110

of rectangular cross section as shown in Fig. 9, and at the point of connection with the link 28, the ring is formed with a round portion 30 over which the eye of the link 28 engages. This round portion effectively prevents shifting of the link connection along the ring. Without this device the link 28 tends to slip back against the locking member 20 and jam against it, thereby causing a twisting or bending stress to be applied to the link and ring members; also interfering with the operation of the lock. It will be noted that the locking member has a comparatively loose mounting and at the same time, a secure mounting. This has the advantage of allowing the locking projection 23 to shift slightly of its own accord so as always to register with the space between a pair of interlocking elements 13. Furthermore, if desired, the engaging end of the locking projection 23 may be beveled or rounded on its forward side so that it will jump over the fastener elements when placed under an undue stress which might otherwise break or bend the locking projection.

As a result of our invention it will be observed that a greatly improved locking device for sliders has been devised which is relatively simple in construction and manufacture. It may be mentioned in assembling the device the spring 25a is first assembled with a slider and the locking member is assembled with the fulcrum lug and spring before the projection 24 is bent up in the longitudinal plane, then after the parts are in position, the lug 24 is bent up under the stirrup 25. The device is very durable since there are no parts which can be easily bent or displaced. At the same time, an efficient lock is provided which will always hold the slider in the desired position and will be automatically released without any attention when a pulling force is applied to the flexible pull member in the direction to open the fastener.

While we have in this application specifically described one embodiment which our invention may assume in practice, it will be understood that the embodiment is merely for the purposes of illustration and description and that various other forms may be devised within the scope of our invention as defined in the appended claims.

What we claim as our invention is:

1. A slider for multiple interlocking fasteners comprising a channeled body member movable along the fastener elements, a lug projecting from the upper wing of said slider, an elongated locking and pull attaching member having a fulcrum connection with said lug at one end, and a locking projection at its other end adapted to project into the channel of said body member, means for limiting the outward movement of said locking and pull attaching member, means including a spring acting on said locking member normally tending to hold the same in locking position, and a pull member operatively connected to said locking member and adapted to move the same to released position automatically when the slider is being moved in the opening direction.
2. A slider for multiple interlocking fasteners having interlocking elements comprising a channeled body member movable along the fastener strings, an elongated locking and pull attaching members movably mounted on said slider body, having a fulcrum projection at one end and at its other end a locking projection adapted in one position of the member to

project into locking engagement with the interlocking elements, means providing a fulcrum on said body member for engagement with said fulcrum projection, a spring on said body member and acting on said locking member at a point spaced from the fulcrum end toward the locking projection end and tending normally to hold the locking projection in engagement with the fastener elements, and a pull member connected to said locking member for actuating the slider, and adapted also to move said locking member into released position when a pulling force is applied thereto in opening the fastener.

3. A slider for multiple interlocking fasteners comprising a channeled body member movable along the fastener elements, a fulcrum lug on the upper wing of said slider and having an aperture therein, an elongated locking member having a projection loosely engaged in said aperture, the other end of said locking member having a projection adapted to extend into the channel of said body member, a spring anchored to said body member acting on said locking member at the end having the locking projection and tending normally to hold the locking projection in locking position, and a pull member, attached to said locking member for actuating the slider and adapted when a pulling force is applied thereto in opening the fastener, to release said locking member against the tension of said spring.

4. A slider for multiple interlocking fasteners comprising a channeled body member movable along the fastener elements, an elongated locking and pull attaching member fulcrumed to said slider body at one end, and having at its other end a projection extending at right angles so as to obstruct the channel in said slider body in one position of the locking member, and a longitudinally extending projection cooperating with means on the body member to limit outward movement of said locking member with respect to the body member, a spring anchored to said body member and normally holding said locking member in locking position, and a pull member connected to said locking member for actuating the slider and simultaneously moving said locking member upwardly against the tension of said spring to release said lock when a pulling force is applied in opening the fastener.

5. A slider for multiple interlocking fasteners constructed according to the preceding claim wherein the means on the body member for limiting outward movement of the locking member includes a stirrup adapted to engage over said longitudinal projection on the locking member.

6. A slider for multiple interlocking fasteners constructed in accordance with claim 4 in which said elongated locking member is formed from a T section bar providing guide grooves intermediate the ends with which said pull member is slidably engaged.

7. A slider for multiple interlocking fasteners comprising a channeled body member movable along the fastener elements, a flexible pull member for actuating said slider including a ring pivoted to said body member in such a manner as to prevent the rotation of the ring about its axis, means flexibly connecting said flexible pull member with said ring, means confining said connecting means for preventing said connecting means from traveling to the end portions of said ring.

GIDEON SUNDBACK.
GUSTAF DAHLIN.
